UNITED STATES PATENT OFFICE.

JOSEPH L. BANGLEY, OF NORFOLK, VIRGINIA, ASSIGNOR OF ONE-HALF TO
HARRY SMITH, OF SAME PLACE.

PRINTING DEVICE FOR PAPER-ROLL HOLDERS.

SPECIFICATION forming part of Letters Patent No. 643,369, dated February 13, 1900.

Application filed March 24, 1899. Serial No. 710,317. (No model.)

To all whom it may concern:

Be it known that I, JOSEPH L. BANGLEY, a citizen of the United States, residing at Norfolk, in the county of Norfolk and State of Virginia, have invented a new and useful 5 Printing Device for Paper-Roll Holders, of which the following is a specification.

The invention relates to improvements in printing devices for paper-roll holders.

10 The object of the present invention is to improve the construction of printing devices for paper-roll holders and to provide an exceedingly simple and inexpensive device adapted to be readily applied to any ordinary paper- 15 roll holder and capable of ready adjustment to arrange it in proper position for printing advertising or other matter on the paper as it is unreeled for use.

The invention consists in the construction 20 and novel combination and arrangement of parts hereinafter fully described, illustrated in the accompanying drawings, and pointed out in the claims hereto appended.

In the drawings, Figure 1 is a perspective 25 view of a printing device constructed in accordance with this invention. Fig. 2 is a side elevation, partly in section. Fig. 3 is a perspective view showing the printing device applied to a paper-roll holder.

30 Like numerals of reference designate corresponding parts in all the figures of the drawings.

1 designates a supporting-frame comprising similar sides 2 and an outer connecting-bar 3, 35 said sides being provided with upwardly-extending arms 4, provided with bearing-slots 5, receiving the journals 6 of an inking-roll 7. The inking-roll 7 is located above a printing-roll 8, which is journaled between the sides 2 40 of the supporting-frame, preferably on a rod or shaft 9, which connects the sides of the frame. The printing - roller, which is provided on its engaging face or periphery with suitable type, frictionally meshes with and 45 engages the inking-roll, which rests upon the printing-roll. The arms, which extend upward from the sides of the frame, loosely receive the journals of the inking-roll, which is held in engagement with the printing-roll by 50 gravity. The rolls are provided at their ends with annular enlargements 10 and 11, form-

ing friction-wheels, whereby when the printing-roll is rotated through contact with the paper of a paper-roll holder the inking-roll will be rotated to supply the type with ink. 55 The type 13 is set in the recess between the enlargements 11 of the printing-roll, and the ink-pad, which supplies the type with ink, is arranged out of contact with the surface of the printing-roll, so that there is no liability 60 of smearing ink on unprinted portions of the paper.

In order to enable the printing device to be readily mounted on any ordinary paper-roll holder, as illustrated in Fig. 3 of the accompanying drawings, in position to print an advertisement or other matter on the paper as it is unreeled, it is provided with a pair of adjustable clamps 14, mounted on the connecting-bar of the supporting-frame. The 70 clamps, which are substantially U-shaped, are arranged to straddle and engage the upper edge of the blade 19 of the paper-roll holder 20, and they are fastened to the same by clamping-screws 15, mounted on the outer 75 sides of the clamps in threaded openings of the same. The clamps are provided with arms 16, having longitudinal slots 17, and disposed transversely of the connecting-bar 3, being secured to the same by bolts 18 or 80 other suitable fastening devices.

The fastening devices 18, which pass through the slots of the arms of the clamps, enable the latter to be adjusted to and from the supporting-frame in order to position the 85 inking device, so that the type will make a clear impression on the paper of a roll as it is unreeled. The arms of the clamps are designed to be constructed of brass or other suitable material which is pliable and adapted to 90 enable the device to be set at an angle. By bending the arms and by adjusting them on the supporting-frame the inking device may be readily placed in position for printing properly on a roll of paper. As it is mounted on 95 the knife or blade, it adjusts itself automatically with the same and approaches the center of the roll as the paper is consumed, so that it will properly engage the paper at all times until the same is entirely consumed. 100

The invention has the following advantages: The inking device, which is exceed-

ingly simple and inexpensive in construction, is adapted to be readily applied to the blade of a paper-roll holder, and it is capable of being quickly positioned to print properly on the paper as it is unreeled. The device dispenses with springs, as the inking-roll is held in engagement with the printing-roll by gravity, and the clamps are capable of adjustment on the connecting-bar of the frame and may 5 be also bent in order to set the device properly. After the device is once adjusted to a paper-roll holder it will operate automatically and give perfect impressions until the entire roll of paper is consumed. The inking-roll is removably mounted in the slots of the arms of the frame and may be readily detached to supply the pad with ink.

Changes in the form, proportion, size, and the minor details of construction within the 20 scope of the appended claims may be resorted to without departing from the spirit or sacrificing any of the advantages of this invention.

What I claim is—

1. A device of the class described comprising a supporting-frame, inking and printing rolls, and a pair of clamps arranged to engage the knife of a paper-roll holder and provided with arms detachably secured to the supporting-frame and capable of adjustment thereon, 25 substantially as and for the purpose described.

2. A device of the class described comprising a supporting-frame, printing and inking rolls, clamps arranged to engage the blade or knife of a paper-roll holder and provided with 30

pliable arms having longitudinal slots and 35 adapted to be deflected by bending, and fastening devices passing through the slots and securing the clamps to the supporting-frame, substantially as described.

3. A device of the class described comprising a frame provided with arms having slots, a printing-roll journaled in the frame, an inking-roll having journals loosely arranged in the slots, whereby the said inking-roll is adapted to rest upon the printing-roll, a pair 40 of clamps arranged to engage the blade or knife of a paper-roll holder and provided with arms, and means for adjustably securing the arms to the supporting-frame, substantially 45 as described.

4. The combination with a paper-roll holder, of a supporting-frame provided at the front with a depending clamp, adjustably engaging the knife of the paper-roll holder, said supporting-frame extending inward from the said 50 knife over the roll of paper, and the printing and inking rolls mounted in the supporting-frame, the printing-roll being in contact with the paper, substantially as and for the purpose described.

In testimony that I claim the foregoing as my own I have hereto affixed my signature in the presence of two witnesses.

JOSEPH L. BANGLEY.
